CUFF LINK

Frederick W. Moulson, Rehoboth, Mass., assignor to B. A. Ballou & Co. Incorporated, a corporation of Rhode Island

Application July 20, 1954, Serial No. 31,500

Term of patent 14 years

(Cl. D17—7)

Fig. 1.

Fig. 2.

The essential features of my design are shown in full lines.

I claim:

The ornamental design for a cuff link, substantially as shown and described.
